(74) Attorney, Agent, or Firm — Michael Best & Friedrich LLP

(57) **CLAIM**

The ornamental design for a UTV ride-on toy, as shown and described.

DESCRIPTION

FIG. 1 is a front perspective view of an embodiment of the design;

FIG. 2 is a rear perspective view of FIG. 1;

FIG. 3 is a front elevational view of FIG. 1;

FIG. 4 is a rear elevational view of FIG. 1;

FIG. 5 is a left-side elevational view of FIG. 1;

FIG. 6 is a right-side elevational view of FIG. 1;

FIG. 7 is a top plan view of FIG. 1;

FIG. 8 is a front perspective view of a second embodiment of the design;

FIG. 9 is a rear perspective view of FIG. 8;

FIG. 10 is a front elevational view of FIG. 8;

FIG. 11 is a rear elevational view of FIG. 8;

FIG. 12 is a left-side elevational view of FIG. 8;

FIG. 13 is a right-side elevational view of FIG. 8; and,

FIG. 14 is a top plan view of FIG. 8.

The broken lines show portions of the UTV ride-on toy that form no part of the claimed design.
